UNITED STATES PATENT OFFICE.

GEORGE W. DICKIE, OF SAN FRANCISCO, CALIFORNIA, ASSIGNOR TO THE UNION IRON WORKS, OF SAME PLACE.

APPARATUS FOR OPERATING GUN-TURRETS.

SPECIFICATION forming part of Letters Patent No. 599,600, dated February 22, 1898.

Application filed August 23, 1897. Serial No. 649,183. (No model.)

To all whom it may concern:

Be it known that I, GEORGE W. DICKIE, a citizen of the United States, and a resident of the city and county of San Francisco, State 5 of California, have invented certain new and useful Apparatus to Control the Operation of Armored Gun-Turrets or Like Heavy Masses; and I hereby declare the following specification and the drawings therewith to be a complete 10 description of my invention and the manner of its application.

My invention relates especially to operating armored gun-turrets by motive power not positive in its action, as by electric motors or 15 steam or air engines, and to attaining in such cases a positive control of the mass moved in respect to velocity, range, and holding it in a fixed position; also, in combination with such control, means of communicating the driving 20 power to the turret or mass to be moved and operated.

My improvements consist of hydraulic apparatus through which liquid is circulated coincident with the turret's movements, controlling 25 the speed and range of such movements; also, in providing by means of pass-over or escape valves in such apparatus to cushion the momentum of the moving mass, and in conjunction therewith electric motors 30 having different speeds of rotation and voltage to gradually overcome the inertia of the mass to be moved without an excess of electric current, and in other features of a constructive and operative nature, as hereinafter 35 more fully explained and pointed out in connection with the drawings, and set forth in the claims at the end of this specification.

The object of my invention is to enable the application of electric, steam, pneumatic, 40 or other non-positive driving power to the operation of armored gun-turrets or other heavy masses to be moved intermittently at various speeds and held in a fixed position by the same agent or apparatus.

In the movement of heavy masses, especially armored revolving turrets for heavy guns, the common means of attaining such movement has been by hydraulic apparatus operating by means of an inelastic fluid that 45 by its nature produces positive and coincident motion of the impelling agent and the

mass to be moved or driven. In performing this function by means of an elastic fluid or other non-positive connection, as in the case of electric motors, there is, besides the want 55 of a definite range of movement, the impediment of overcoming the inertia and resisting the momentum of the mass, so as to attain control without endangering the connection or means of transmission; also, of attaining 60 precision, a variable rate of movement, and locking the turret or mass in a fixed position. To avoid these objections and attain the required functions in the motive apparatus, I provide devices as are herewith illustrated. 65

Referring to the drawings, Figure I is a diagram in which the various elements and parts involved in my invention are so arranged as to show their connection and relation to an enlarged scale and to enable plain description. Fig. II is a vertical section through an armored turret arranged to be driven by an electric motor and in which my invention is applied. Fig. III is a horizontal section on the line *a b* in Fig. II. Fig. IV is a broken plan 70 view of a portion of a marine turret, showing the situation of my improved controlling apparatus mounted therein. Fig. V is a vertical section through one side of the same turret, showing a view of my improved controlling apparatus at a right angle to Fig. IV. Fig. VI is a view of one of the hydraulic cylinders detached and shown at a right angle to the position in Fig. V. 75

Similar numerals of reference are applied 80 to corresponding parts in the different figures of the drawings.

In turning armored turrets to attain the desired angle or line of fire, also in their adjustment and retention in a fixed position, there 90 is required a positive limitation and control of such movements not attainable by engines operated by elastic fluids or by means of transmission that are not positive, such as frictional devices or electric motors. It is therefore necessary to provide separate means of controlling the motion of such turrets as to range and fixed positions; also, to absorb their momentum when set in motion at a rate that would endanger the connecting-gearing if 95 suddenly stopped. It is also desirable in the case of heavy turrets operated by electric mo-

tors to provide for a cumulative actuating force that will in starting gradually overcome the inertia of the mass and set it in motion without passing through the electric motor a 5 volume of current that would endanger the insulation of the electric motor. To these ends I provide apparatus and devices as shown in the drawings, 1 being the revolute portion of a turret; 2, the stationary armor; 10 3, the operating deck or platform within the turret, and 4 gun-ports in the revolving part thereof.

The revolute part 1 of the turret is connected to the platform 3 by means of strong 15 framing 5 and is integral therewith, the weight of the whole being supported on the rollers 6, that rest on the circular supporting-ways 7, mounted on the framing 8, that extends down to the deck or floor 9, as seen 20 in Fig. II. The open ways 10 in the platform 3 are to permit depression of the breeches of the guns when housed and in loading.

The turret is turned by means of a strong pinion or pinions 11, that mesh into circular 25 stationary rack 12, as seen in Fig. I, to which reference will now be made. In this figure and diagram the apparatus illustrated is to show the manner of operating, some of the parts not corresponding to their position in 30 other figures of the drawings and one pair of wheels 13 and 14 in the train of gearing being omitted.

Beginning with the elements for transmitting power and turning the turret, 15 is a 35 small electric motor arranged to run at a high rate of speed. A pinion 17 on the armature-shaft 18 of this motor gears into the wheel 19 on the armature-shaft 20 of a large electric motor 21, a clutch 22 being provided to connect or fasten the wheel 19 to the shaft 20, for purposes hereinafter explained. On one 40 end of the armature-shaft 20 is a bevel-pinion 23, meshing into the wheel 24 on the shaft 25. On the other end of this shaft 25 is a spur 45 pinion 26, that drives the wheel 27, the shaft 28, and the pinion 11, which latter meshes into the circular stationary rack 12, as before explained. This forms a connected train of transmission from the motors 15 and 21 to the 50 rack 12.

Supposing the turret to weigh five hundred tons, which many of them exceed, and that the motor 21 has a rate of four hundred revolutions per minute, it is evident that the mass 55 must be set in motion at a rate much slower than the operating conditions of the main electric motor 21 permit. To evade this difficulty, the smaller electric motor 15, with a higher rate of revolution, is introduced and 60 is, as before explained, geared to the main motor by the wheels 17 19, these being in relation as the normal rates of speed for the motors 15 and 21.

In starting the turret the electric current is 65 sent into the motor 15, and at the same time to a solenoid 16, which operates and closes the clutch 22 by means of the tri-armed lever

29, thus setting the main motor 21 in revolution, and with it the train of gearing down to the rack 12, revolving the turret accordingly. 70 When the main motor 21 has attained a rate of revolution suited to its electrical conditions, or approximately so, the electric current is cut out from the motor 15 and from the solenoid 16, and by the same motion the 75 circuit is closed to the main motor 21. The spring 43 then disengages the clutch 22, moving it to the position seen in the drawings, and the shaft 20 runs free. The main motor then continues the movement commenced by 80 the auxiliary motor 15. This comprises the method and apparatus of transmitting and applying power to move the turret by means of an electric current. As, however, power applied to turning the turret in this manner 85 is flexible and not determinate as to speed, range, and other limitations of firing, a positive control of such motions is essential and must be otherwise provided. Such control I provide by means of hydraulic apparatus represented in Fig. I by the cylinders 30 31 and their accessories, now to be described. These cylinders 30 31 are provided with the usual pistons and connections to the cranks 32 33, formed in the shaft 28, and set at an angle of 90 ninety degrees, as shown. These cylinders being filled with an incompressible fluid, such as water or oil, it is evident that rotation of the shaft 28 must produce a circulation or 100 transfer of the fluid from one end to the other of the cylinders 30 31 or from one side to the other of the pistons therein. Such circulation is permitted by the pipes 34 35, that connect the ends of the cylinders 30 31 and are provided with cocks or valves 36 37 to regulate 105 the rate at which the fluid can be transferred from one side of the pistons to the other, and consequently control the rate and distance of the movement of the machinery and of the turret impelled thereby. The cocks 36 37 are operated by a rod or connection 38, extending to 110 a place from which the movements of the machinery and the turret are controlled, and by connection with the switches that open and close the electric circuit the actuating and 115 controlling elements may operate coincident by means of single lever or other device at the place of control 42.

The momentum of the turret when set in motion at the rate required or desirable for 120 long ranges of arc is such that if the cocks 36 37 are suddenly closed and movement stopped the machinery would be endangered by the shock. To provide for this contingency, I employ a second set of pass-over or connecting pipes 39 40, communicating between the ends of the cylinders 31 32, two pipes on each cylinder, provided with check-valves 41, one in each pipe, that act automatically to permit flow in one direction only. These valves 41 are 125 held shut by springs 45, so adjusted that the valves will open at some predetermined pressure that the machinery is able to overcome without danger of accident, so that if the con- 130

trol-cocks 36 37 are closed too suddenly the valves 41 open and permit flow from one end to the other of the cylinders 30 31 until the pressure falls to a point of safety. Then the 5 valves 41 will close automatically and the valves or cocks 36 37 will resume control.

To simplify illustration I have in Fig. I shown the hydraulic cylinders 30 31 side by side and as adapted for turning gearing to 10 operate at one side of a turret. If, however, turning-gearing is provided at both sides of the turret, as is common in practice, then these cylinders 30 31 and their accessories can be placed one at each side of the turret and 15 operate in the same manner, provided their cranks 32 33 are formed in corresponding shafts and at an angle of ninety degrees, as shown. These operating and other parts illustrated in the diagram, Fig. I, can be traced 20 by corresponding references and by their connection in the other views, Figs. II to VI of the drawings, the arrangement being modified so as to admit the machinery into a contracted space on shipboard and demanding a scale 25 for the drawings too small for plain illustration, easily understood, however, by any one skilled in this branch of construction.

It will be seen and understood that the hydraulic controlling elements of my invention 30 are equally applicable to turret-moving machinery impelled by steam, air, or gas engines or any other means not positive in its nature and connections, such application in both 35 method and apparatus remaining substantially the same as to its construction and functions. It will also be understood that other forms of hydraulic apparatus, such as positive rotary pumps, could be employed instead of reciprocating pistons. The latter 40 are, however, preferable and more secure against leaking, which would cause false movement of the machinery and of the turret.

In the case of stationary structures or turrets erected on land the arrangement of the 45 various parts would be quite different from that shown in Figs. IV and V. I do not, therefore, confine myself to a particular arrangement of the machinery and parts thereof; but

I claim as my invention and desire to secure 50 by Letters Patent—

1. In a gun-turret operated by machinery, a superimposed armored section, capable of turning to produce various angles of fire, motive apparatus therein and turning-gearing 55 to transmit motion from the motive apparatus to the turret, and in combination therewith hydraulic controlling devices so connected to the turning-gearing as to control positively the range and rate of the turret's

movement, in the manner and for the purposes substantially as described. 60

2. In turret-operating machinery, main and auxiliary electric motors, means to connect and disengage the same, gearing to connect these motors to the turret-moving devices, 65 and in combination therewith hydraulic apparatus to control movements of the machinery and turret, in the manner substantially and for the purposes described.

3. In turret-operating machinery, an electric motor or motors to operate the turning mechanism, a train of gearing connecting the motor or motors with the circular stationary rack by means of which the turret is operated, and in combination therewith hydraulic 75 cylinders and pistons that positively control and regulate the motion of the machinery and the turret, in the manner substantially as set forth and described.

4. In gun-turret-operating machinery, a motive apparatus and gearing to transmit and apply power to produce motion of the turret, and in combination therewith hydraulic apparatus provided with pass-over or transfer pipes or passages so the fluid in the hydraulic apparatus can circulate therein and permit movement of the turret positively and coincident with such circulation, substantially as specified. 80 85

5. In a gun-turret operated by machinery, 90 a revoluble turret and motive apparatus to turn the same, gearing to connect the motive apparatus and turret, and hydraulic devices to control and regulate the motion of these, and in combination therewith relief-valves 95 on the hydraulic apparatus that will open and permit circulation of the fluid therein when the pressure exceeds some predetermined amount, substantially as described.

6. In a gun-turret operated by machinery, 100 a revoluble turret-section adapted to train the guns horizontally, motive apparatus to turn the turret, and gearing to connect the two, hydraulic apparatus to limit and control movements of the machinery and turret, 105 the hydraulic apparatus provided with adjustable circulating-valves to govern movements of the machinery and turret, and also with automatic relief-valves to guard against overpressure, all combined and operating in 110 the manner substantially as described.

In testimony whereof I have hereunto affixed my signature in the presence of two witnesses.

GEORGE W. DICKIE.
